LOCK FOR SLIDABLE CLOSURES

Kenneth M. Christensen, Minneapolis, Minn., and John W. Binns, Hartford City, Ind., assignors to Overhead Door Corporation, Hartford City, Ind.

Filed Apr. 10, 1961, Ser. No. 101,942

12 Claims. (Cl. 292—113)

This invention relates to a lock for slidable closures such, for example, as upwardly acting doors. The main objects of this invention are,

First, to provide a lock for slidable closures which is adapted to be locked in closed position and to receive a seal, there being, when manipulated or used as designed to be used, no strain upon the seal likely to break or fracture the same.

Second, to provide a lock means for slidable closures which is easily manipulated to and from locking position and is automatically held when adjusted to locking position so that a seal or padlock, or the like, may be applied.

Third, to provide a securing means for slidable closures adapted to receive a seal which cannot be opened without breaking the seal.

Fourth, to provide a lock structure having these advantages which is relatively simple in its parts and easily manipulated in use.

Objects relating to details and economies of the invention will appear from the description to follow. The invention is defined and pointed out in the claims. A preferred embodiment of the invention is illustrated in the accompanying drawing, in which:

FIG. 1 is a fragmentary front elevational view of an upwardly acting door structure embodying our invention, the door structure, including the sill, frame and door, being shown conventionally.

FIG. 2 is an enlarged fragmentary view on a line corresponding to line 2—2 of FIG. 1.

FIG. 3 is a fragmentary view on a line corresponding to line 3—3 of FIG. 1.

FIG. 4 is an enlarged fragmentary view on a line corresponding to line 4—4 of FIG. 1.

FIG. 5 is an enlarged fragmentary view partially in vertical section with the lock member in released position.

FIG. 6 is a fragmentary view in section on a line corresponding to line 6—6 of FIG. 3.

FIG. 7 is a fragmentary view on a line corresponding to line 7—7 of FIGS. 2 and 3.

FIG. 8 is a fragmentary view in section on a line corresponding to line 8—8 of FIG. 1.

FIG. 9 is a fragmentary sectional view in which the seal has been erroneously or intentionally mispositioned.

FIG. 10 is a fragmentary view corresponding to that of FIG. 9, illustrating that the bolt cannot be disengaged from the keeper without breaking the seal.

In the accompanying drawing we have illustrated our invention as embodied in an upwardly acting door of the sectional type in which 1 represents a door frame, 2 the sill and 3 and 4 sections of a door, 4 being the bottom section of the door. The bottom section 4 is desirably provided with a resilient sill engaging member 5 on its bottom edge, which is conventionally shown. The embodiment of our invention illustrated comprises a base member 6 which is fixedly secured to the closure member by fasteners indicated conventionally at 7. This base member is formed of sheet stock and has an outwardly offset embossment 8 perforated to receive the pivot 9, which is secured by means of the nut 10 threaded upon its inner end and housed within the embossment 8. The pivot has a head 11 on its outer end.

The bolt support member, designated generally by the numeral 12, is desirably formed as an integral casting and has a laterally projecting integral handle 13. This sup-

2

port member has a laterally opening chamber 14 therein opening oppositely to the handle and which includes an inwardly projecting side wall 15 providing a housing for the coil spring 16, arranged around the embossment 8 and having its inner end 17 engaged in a slot 18 in the embossment, see FIG. 2, and its outer end 19 engaged with the inner end of the pivot 20 mounted on the bolt support member and constituting a support for the bolt 21, see FIGS. 2 and 5. The pivot 20 of the bolt 21 is disposed radially relative to the pivot 9 of the bolt support member. In the embodiment illustrated, the keeper 23 is in the form of a rod which is disposed transversely within the housing 23 which is set into the sill. The keeper engaging member 22 has an upwardly facing recess 22' therein which is in effect in interlocking engagement with the keeper when the lock is in closed keeper engaging position, as is illustrated in FIGS. 1 and 9, the bolt being also shown in keeper engaging position by dotted lines in FIG. 5.

It will be understood that the spring 16 acts to disengage the bolt from the keeper and to automatically swing the bolt support member to its retracted position, as shown in FIG. 5, in which position the bolt engages the combined stop and lock receiving member 24 which in the embodiment illustrated is struck out from the base member. The bolt is yieldingly urged against the stop 25 on the support member by the coil spring 26, which is engaged with a hook 27 on the bolt and supportedly connected on the handle by the stud 28, the inner end of the handle being recessed at 29 to receive the spring. When in actuated position, the bolt is engaged by the stop or thrust member 30 on the bolt support member. The stop 24 also serves as a stop for the handle when the bolt is in actuated or keeper engaging position. When the handle is swung to bolt actuated position, it is automatically engaged by the latch 31 which is pivoted on the base member at 32 in upwardly and laterally spaced relation to the member 24, and is actuated by the spring 33 mounted on the bracket or lug 34 which, in the embodiment illustrated, is struck out from the base member. The handle is provided with a keeper 35 with which this latch automatically engages when the handle is swung to bolt actuated position and in supported relation to the stop member 24, see FIG. 1. This latch 31 is provided with an upwardly projecting finger piece 36. The handle is provided with a locking lug 37 projecting therefrom and positioned to be disposed in side by side relation to the stop 24 when the handle is in bolt actuating position, this lug having an opening 38 therein, the stop having an aligned opening therein adapted to receive a padlock or other locking member or element 39, a seal member, or both, the padlock only being illustrated in FIG. 1.

The handle of this embodiment is provided with a hole 40 at its outer end adapted to receive a seal member conventionally shown at 41 in FIG. 1, the sill being provided with a strap 42 with which the seal may be engaged. The seal and the strap are conventionally shown. It will be understood that seals are widely used on conveyances and they do not constitute locking means for holding the parts in closed position, but merely to indicate whether or not the conveyance had been opened. The applicants' locking means are especially designed for use in upwardly acting doors of vehicles but may be used as a locking means for doors on buildings. One of the attained objects of the invention is the rapidity and ease of operation. With the lock 39 disengaged, the operator disengages the latch and the bolt support member is swung to bolt retracting position, as illustrated in FIG. 5, the bolt then engaging the stop member 24. To engage the bolt it is only necessary to swing the handle into engagement with the stop member 24, and the latch automatically engages to retain the bolt in locked position, permitting

the operator to apply the padlock or other locking element, or a seal, or both as may be desired.

The correct and desired positioning of the seal 41 is illustrated in FIG. 1, however, manipulators may either accidentally or intentionally position the seal as is shown in FIGS. 9 and 10. When that is done, even though the seal is in such position as to permit the releasing or disengagement of the latch 31 and the upward swinging of the handle as is indicated in FIG. 10, as far as the seal will permit without breaking, the bolt cannot be disengaged from the keeper, see FIG. 10. As stated, it is intended that the seal be positioned as illustrated in FIG. 1 and that a lock 39 be used where desired, but in the event that the seal is positioned as in FIGS. 9 and 10 the door cannot be opened without breaking or fracturing the seal.

We have illustrated and described our invention in a highly practical commercial embodiment thereof. We have not illustrated or described certain modifications and adaptations in structural details, as it is believed that this disclosure will enable those skilled in the art to embody our invention as may be desired.

Having thus described the invention, what is claimed as new and desired to secure by Letters Patent is:

1. A lock comprising a base member having a bolt support member pivot projecting outwardly therefrom, a bolt support member rotatably mounted on said pivot and having a laterally projecting handle, said bolt support member having a bolt receiving recess therein opening at its edge opposite said handle, a coil retracting spring for said bolt support member disposed in embracing relation to said pivot with one end thereof connected to said base member and the other to said bolt support member, a bolt disposed with its inner end within said bolt support member and pivotally connected thereto in radially spaced relation to its said bolt support member pivot, said bolt having a keeper-engaging jaw, said bolt support member having a bolt retracting lug radially spaced from said bolt support member pivot and having a bolt holder lug disposed to engage said bolt when said bolt support member is actuated to position the bolt in its keeper-engaging position, a spring connected to said bolt support member and to said bolt and acting to yieldingly urge it against said bolt retracting lug, a stop on said base member positioned to be engaged by said bolt with said bolt in engagement with said retracting lug thereby limiting the opening movement of said bolt support member and to be engaged by said handle when said bolt support member is adjusted to position said bolt in keeper-engaging position, said handle having a lug thereon which is disposed adjacent said stop on said base member when said support member is positioned to actuate said bolt to keeper-engaging position, said stop on said support member and said lug on said handle having aligned openings therein adapted to receive locking means, and a manually releasable spring actuated latch pivotally mounted on said base member, said handle having a keeper which said latch automatically engages when the handle is adjusted to position said bolt in keeper engaging position.

2. A lock comprising a base member having a bolt support member pivot projecting outwardly therefrom, a bolt support member rotatably mounted on said pivot and having a laterally projecting handle, said bolt support member having a bolt receiving recess therein opening at its edge opposite said handle, a coil retracting spring for said bolt support member disposed in embracing relation to said pivot with one end thereof connected to said base member and the other to said bolt support member, a bolt disposed with its inner end within said bolt support member and pivotally connected thereto in radially spaced relation to its said bolt support member pivot, said bolt having a keeper-engaging jaw, said bolt support member having a bolt retracting lug radially spaced from said bolt support member pivot and having a bolt holder lug disposed to engage said bolt when said bolt support member is positioned to actuate said bolt to keeper-engaging position, said stop on said support member and said lug on said handle having aligned openings therein adapted to receive locking means, and a manually releasable spring actuated latch pivotally mounted on said base member, said handle having a keeper which said latch automatically engages when the handle is adjusted to position said bolt in keeper engaging position.

is actuated to position the bolt in its keeper-engaging position, a spring connected to said bolt support member and to said bolt and acting to yieldingly urge it against said bolt retracting lug, a stop on said base member positioned to be engaged by said bolt with said bolt in engagement with said retracting lug thereby limiting the opening movement of said bolt support member and to be engaged by said handle when said bolt support member is adjusted to position said bolt in keeper-engaging position, said handle having a lug thereon which is disposed adjacent said stop on said base member when said support member is positioned to actuate said bolt to keeper-engaging position, and a manually releasable spring actuated latch pivotally mounted on said base member, said handle having a keeper which said latch automatically engages when the handle is adjusted to position said bolt in keeper engaging position.

3. A lock comprising a base member having a bolt support member pivot projecting outwardly therefrom, a bolt support member rotatably mounted on said pivot and having a laterally projecting handle, said bolt support member having a bolt receiving recess therein opening at its edge opposite said handle, a coil retracting spring for said bolt support member disposed in embracing relation to said pivot with one end thereof connected to said base member and the other to said bolt support member, a bolt disposed with its inner end within said bolt support member and pivotally connected thereto in radially spaced relation to its said bolt support member pivot, said bolt having a keeper-engaging jaw mounted on its outer end for adjustment longitudinally thereof, said bolt support member having a bolt retracting lug radially spaced from said bolt support member pivot and having a bolt holder lug disposed to engage said bolt when said bolt support member is actuated to position the bolt in its keeper-engaging position, a spring connected to said bolt support member and to said bolt and acting to yieldingly urge it against said bolt retracting lug, a stop on said base member positioned to be engaged by said bolt with said bolt in engagement with said retracting lug thereby limiting the opening movement of said bolt support member and to be engaged by said handle when said bolt support member is adjusted to position said bolt in keeper-engaging position, said handle having a lug thereon which is disposed adjacent said stop on said base member when said support member is positioned to actuate said bolt to keeper-engaging position, and a manually releasable spring actuated latch pivotally mounted on said base member, said handle having a keeper which said latch automatically engages when the handle is adjusted to position said bolt in keeper engaging position.

4. A lock comprising a base member having a bolt support member pivot, a manually adjustable bolt support rotatably mounted on said pivot, said bolt support member having a bolt receiving recess therein opening at its edge, a retracting spring for said bolt support member housed therein and supportedly engaged with said pivot with one end thereof connected to said base member and the other to said bolt support member, a bolt disposed with its inner end within and pivotally connected to said bolt support member in radially spaced relation to its said pivot, said bolt having a keeper-engaging jaw, said bolt support member having a bolt retracting lug and having a bolt holder lug disposed to engage said bolt when it is in keeper-engaging position, a spring supportedly connected to said bolt support member and coacting with said bolt to yieldingly urge it against said bolt retracting lug, said base member having a stop positioned to be engaged by said bolt with said bolt in engagement with said retracting lug and thereby limit the opening stroke of said bolt support member and engaged by said bolt support member when it is adjusted to position said bolt in keeper-engaging position, said support member having a lug thereon positioned adjacent said stop on said base when said support member is positioned to actuate said

bolt to keeper-engaging position, said stop on said support member and said lug on said support member being adapted to receive locking means, and a manually releasable automatically engageable latch mounted on said base member to automatically engage said bolt support member when it is adjusted to position said bolt in keeper-engaging position.

5. A lock comprising a base member having a bolt support member pivot, a manually adjustable bolt support rotatably mounted on said pivot, said bolt support member having a bolt receiving recess therein opening at its edge, a retracting spring for said bolt support member housed therein and supportedly engaged with said pivot with one end thereof connected to said base member and the other to said bolt support member, a bolt disposed with its inner end within and pivotally connected to said bolt support member in radially spaced relation to its said pivot, said bolt having a keeper-engaging jaw, said bolt support member having a bolt retracting lug and having a bolt holder lug disposed to engage said bolt when it is in keeper-engaging position, a spring supportedly connected to said bolt support member and coacting with said bolt to yieldingly urge it against said bolt retracting lug, said base member having a stop positioned to be engaged by said bolt with said bolt in engagement with said retracting lug and thereby limit the opening stroke of said bolt support member and engaged by said bolt support member when it is adjusted to position said bolt in keeper-engaging position, and a manually releasable automatically engageable latch mounted on said base member to automatically engage said bolt support member when it is adjusted to position said bolt in keeper-engaging position.

6. A lock comprising a base member having a bolt support member pivot, a manually adjustable bolt support rotatably mounted on said pivot, said bolt support member having a bolt receiving recess therein opening at its edge, a retracting spring for said bolt support member housed therein and supportedly engaged with said pivot with one end thereof connected to said base member and the other to said bolt support member, a bolt disposed with its inner end within and pivotally connected to said bolt support member in radially spaced relation to its said pivot, said bolt having a keeper-engaging jaw mounted thereon for adjustment longitudinally thereof, said bolt support member having a bolt retracting lug and having a bolt holder lug disposed to engage said bolt when it is in keeper-engaging position, a spring supportedly connected to said bolt support member and coacting with said bolt to yieldingly urge it against said bolt retracting lug, said base member having a stop positioned to be engaged by said bolt with said bolt in engagement with said retracting lug and thereby limit the opening stroke of said bolt support member and engaged by said bolt support member when it is adjusted to position said bolt in keeper-engaging position, and a manually releasable automatically engageable latch mounted on said base member to automatically engage said bolt support member when it is adjusted to position said bolt in keeper-engaging position.

7. A lock comprising, a base member having a bolt support member pivot, a manually adjustable bolt support member rotatably mounted on said pivot, a retracting spring for said bolt support member operatively connected thereto and to said base member, a bolt pivotally connected to said bolt support member in radially spaced relation to its said pivot, said bolt support member having a bolt retracting lug and having a bolt holder lug disposed to engage said bolt which is in keeper-engaging position, a spring connected to said bolt support member and bolt to yieldingly urge it against said bolt retracting lug, said base member having a stop member disposed to be engaged by said bolt with said bolt in engagement with said retracting lug, thereby limiting the opening stroke of said bolt support member and a stop engaged by said bolt support member when it is adjusted

to position said bolt in keeper-engaging position, said support member having a lug thereon which is disposed adjacent said stop on said base when said support member is in bolt actuating position, said stop on said support member and said lug on said support member being adapted to receive locking means, and a latch mounted on said base member to engage said bolt support member when it is adjusted to position said bolt in keeper-engaging position.

10. 8. A lock comprising, a base member having a bolt support member pivot, a manually adjustable bolt support member rotatably mounted on said pivot, a retracting spring for said bolt support member operatively connected thereto and to said base member, a bolt pivotally connected to said bolt support member in radially spaced relation to its said pivot, said bolt support member having a bolt retracting lug and having a bolt holder lug disposed to engage said bolt which is in keeper-engaging position, a spring connected to said bolt support member and bolt to yieldingly urge it against said bolt retracting lug, said base member having a stop member disposed to be engaged by said bolt with said bolt in engagement with said retracting lug, thereby limiting the opening stroke of said bolt support member and a stop engaged by said bolt support member when it is adjusted to position said bolt in keeper-engaging position, and a latch mounted on said base member to engage said bolt support member when it is adjusted to position said bolt in keeper-engaging position.
15. 9. A lock comprising a base member, a bolt support member pivotally mounted on said base member and having a laterally projecting handle, a retracting spring for said bolt support member mounted on said base member and operatively connected to said bolt for actuating it to keeper-engaging position, said bolt having a keeper-engaging jaw with a keeper recessed therein of substantial depth, said bolt support member having a bolt retracting lug and having a bolt holder lug disposed to engage the bolt when it is in keeper-engaging position, said bolt support member having a laterally projecting arm which constitutes a handle, said base member having a stop positioned to be engaged by said arm when the bolt is in keeper-engaging position, said arm and said stop on said base member having seal-receiving openings therein, said 20 keeper-engaging recess in said bolt jaw being of such depth that the bolt is not releasably disengaged from the coacting keeper during a substantial degree of bolt releasing movement of said bolt support member to such a degree of bolt releasing movement as would permit disengagement thereof from the coacting keeper without fracturing the seal engageable with said support member and said base member.
25. 10. A lock comprising a base member, a bolt support member pivotally mounted on said base member and having a laterally projecting handle, and a retracting spring for said bolt support member mounted on said base member and operatively connected to said bolt for actuating it to keeper-engaging position, said bolt support member having a bolt retracting lug and having a bolt holder lug disposed to engage the bolt when it is in keeper-engaging position, said bolt support member having a laterally projecting arm which constitutes a handle, said base member having a stop positioned to be engaged by said arm when the bolt is in keeper-engaging position, said stop 30 and said arm having seal openings therein adapted to receive a seal and automatically engaging manually releasable latch means mounted on said base member to automatically engage said handle when it is adjusted to actuate said bolt to keeper engaging position.
35. 11. A lock comprising, a base member adapted for fixed attachment to a door having a bolt support member pivot, a manually adjustable bolt support member rotatably mounted on said pivot, a bolt pivotally connected to said bolt support member in radially spaced relation to its said pivot, said bolt support member hav-
- 75

ing a bolt retracting lug and having a bolt holder lug disposed to engage said bolt when it is in keeper-engaging position, said base member having a stop member disposed to be engaged by said bolt with said bolt in engagement with said retracting lug, thereby limiting the opening stroke of said bolt support member and engaged by said bolt support member when it is adjusted to position said bolt in keeper-engaging position, said support member having a lug thereon which is disposed adjacent said stop member on said base member when said support member is in bolt actuating position, said stop on said base member and said lug on said bolt support member being adapted to receive locking and/or seal means, and automatically engaging manually released means mounted on said base member to automatically engage said bolt support member when it is adjusted to position said bolt in keeper-engaging position.

12. A lock comprising, a base member adapted for fixed attachment to a door having a bolt support member pivot, a manually adjustable bolt support member rotatably mounted on said pivot, a bolt pivotally connected to said bolt support member in radially spaced relation to its said pivot, said bolt support member having a bolt retracting lug and having a bolt holder lug disposed to

engage said bolt when it is in keeper-engaging position, said base member having a stop member disposed to be engaged by said bolt with said bolt in supported engagement with said retracting lug, thereby limiting the opening stroke of said bolt support member and which is engaged by said bolt support member when it is adjusted to position said bolt in keeper-engaging position, and an automatically engaging manually released latch mounted on said base member to retainingly engage said bolt support member when it is adjusted to position said bolt in keeper-engaging position.
